TARGET GAME

Duane William Price and Marvin Kellermann,
Chicago, Ill., assignors, by mesne assignments,
to Frank J. Kolar, South Bend, Ind.

Application April 17, 1933, Serial No. 666,475

11 Claims. (Cl. 273—101)

This invention relates to a target game which is coin freed, which comprises a series of moving targets and a gun adapted to discharge projectiles under the control of the patron. According to the present invention, we associate with each target a prize which is adapted to be released by a correctly directed shot. The machine is desirably electrically operated, and we preferably provide means whereby the gun is rendered inoperative when the current is cut off, so as to prevent cheating by the patron, who might otherwise be able to shoot at a stationary target.

The invention will readily be understood from the following description of a preferred embodiment, taken in conjunction with the accompanying drawings, in which

Fig. 1 is a front elevation of the upper portion of a cabinet embodying the invention;

Fig. 2 is a sectional view through the complete cabinet taken on the line 2—2 of Fig. 1;

Fig. 3 is a sectional view on a larger scale taken on the line 3—3 of Fig. 2;

Fig. 4 is an elevational view, partly in section, of a portion of the target conveyor on a still larger scale; and

Fig. 5 is a detailed sectional plan view of a portion of the gun and related parts.

Referring to the drawings, the machine is enclosed in the cabinet 10, which is provided with a glass window 11 in the upper portion of its front face. The window 11 is the front wall of a compartment 12, which is formed by a portion of the top of the cabinet, portions of the side walls, a vertical partition 13, and a bottom wall 14. The partition 13 is provided with an opening which receives a frame 15. The frame 15 is open so as to present to view targets 16 and prizes 17 associated therewith. The targets 16 and prizes 17 are carried by target carriages 18, the construction of which is best shown in Fig. 4. The carriages 18 depend from bars 19, which are supported at each end upon chains 20 which are continuous so as to provide a continuous conveyor. The chains 20 pass over sprockets 21 which define a substantially rectangular path for the conveyor. The upper pair of sprockets 21 are mounted on shafts 22 which are supported by brackets 23 in the upper portion of the cabinet 10, so that the uppermost horizontal length of the conveyor is located with respect to the frame 15 to bring the target 16 and prize 17 into the view of the patron. The conveyor is driven by one pair, preferably one of the lower pair of sprockets 21, the shaft of which is connected to a gear reduction 24, driven from an electric motor 25.

The target carriage 18 will now be described. This carriage comprises a horizontal portion 26, provided at each end with bosses 27, which freely receive a bar 19. Longitudinal movement of the carriage on the bar 19 is prevented by means of cotter-pins 28. From the forward boss 27 depends an elongated bar 29, the lower end of which is turned forwardly, as best seen in Fig. 4. On this forwardly turned portion is mounted the target 16. The target 16 may suitably consist of a representation of a bird, animal or the like, or it may be a conventional target. In all cases, the target 16 is provided with an opening 30 which defines the bull's-eye. The depending length 29 of the carriage 18 is provided in alignment with the opening 30, with a boss 31 which provides a sliding bearing for a rod 32. The rod 32 carries at its forward end an impact plate 33 which is located immediately behind and in alignment with the opening 30, so that the projectiles hitting the bull's-eye strike the plate 33 and move the rod 32 rearwardly. The rod 32 is normally maintained in its forward position by means of a coil spring 34 which bears against the boss 31 and against the plate 33. The rear end of the rod 32 is connected by a link 35 to the lower end of a lever 36. The lever 36 is pivotally mounted on suitable lugs carried by the depending length 29 of the target carriage 18. The lever 36 is preferably formed from a piece of flat stock, which is bent about its longitudinal axis above its pivot. Adjacent its upper extremity the lever 36 is provided with an opening 37 which freely receives the U bend of a pin or latch 38. The pin or latch 38 is slidably mounted in openings 39 and 40 provided in the upper length 29 and in the boss 27 respectively of the target carriage 18.

The boss 27 is provided in its under side with a slot 41 which extends upwardly above the opening 40. As is best shown in Fig. 4, the prize 17 may be suspended by a loop 42, which loop is passed into the slot 41 and is locked therein by the pin 38. When the plate 33 is hit by a projectile, the lower end of the lever 36 is moved rearwardly and its upper end is moved forwardly. The pin 38 is likewise moved forwardly until its rear end is removed forwardly of the slot 41. The loop 42 is then released and the weight of the prize causes it to fall from the carriage 18.

The bottom wall of the frame 15 is extended rearwardly, as shown in Fig. 2, so as to provide a support for a back plate 43, against which impinge the projectiles which miss the targets. The frame 15 is also provided with a horizontal

web 44, located above the normal level of the target 16 and extending rearwardly of the plane of the targets. Its rear end is preferably turned downwardly so that any projectiles which are ricochetted upwardly strike against the web 44 and are returned to the bottom wall 14 of the chamber 12.

The bottom wall 14 slopes rearwardly so as to feed the projectiles into a tube 45, from which they pass into a gun 46 of known type.

The gun 46 is provided with a universal mounting on a plate 47 secured to the front wall of the cabinet 10 below the window 11. The muzzle of the gun extends into the chamber 12 so that it may be directed toward the cabinet under the control of the patron. The gun may or may not be provided with sights along which the patron may look; that is, the patron may be allowed to look along the sights before firing the gun, or he may be obliged to look through the window 11 and caused to rely upon the results of his shooting to correct his aim.

The gun 46 is provided with a coin slot 48, into which the coin for freeing the mechanism is inserted. The gun comprises a thumb piece 49, which is adapted to be moved forwardly after the coin is inserted, so as to move the coin into the cabinet and discharge it into a coin chute 50, from which it passes to a suitable coin box (not shown). The passage of the coin in this manner is adapted to release a merchandise distributor 51, which is adapted to distribute a measured quantity of candy from a bulk supply in the hopper 52.

The delivery of this merchandise is controlled by a push button 53 and is effected through a chute 54. The front wall of the cabinet 10 is provided with an opening 55 so that the patron may insert his hand in order to receive the candy or other merchandise from the chute 54.

The gun includes a sliding bar 56 which is moved forwardly when the thumb piece 49 is moved forwardly. The sliding bar is adapted to engage, during its forward movement, an arm 57 of a time switch 58 mounted within the cabinet adjacent the forward end of the gun. This time switch completes the circuit of the motor 25 and maintains it in operation for a definite period of time, whereupon the motor automatically stops. Means are provided for preventing operation of the gun when the current is turned off, and thereby prevent the possibility of a patron shooting at a stationary target. Such means may take any suitable form, but in the embodiment shown this means takes the form of a solenoid 59 which is mounted on the forward end of the gun. This solenoid comprises an armature 60 normally pressed outwardly by means of a spring (not shown). The armature 60 is adapted to project into the barrel of the gun, as shown in Fig. 5. When the current is on and the motor is operating the solenoid 59 is energized and the armature 60 is withdrawn from the barrel so that the patron may shoot at the targets.

It will readily be understood that the target 16 is exposed to the patron when it is passing along the opening or the frame 15 and that the prize to be gained by striking the target is likewise exposed. Behind the frame 15 and below the positions of the prizes 17 is provided a hopper 61 which is connected by means of a chute 62 to the pocket 63, so that the prize is delivered to the patron, being accessible through the opening 55.

Although the invention has been described

in connection with specific details of a preferred embodiment thereof, it must be understood that such details are not intended to be limitative of the invention except in so far as set forth in the accompanying claims.

Having thus described our invention, what we claim is new and desire to secure by Letters Patent of the United States, is:

1. A target game comprising a target conveyor, a plurality of targets adapted to be exposed in succession for a limited time, a gun adapted to discharge projectiles towards said targets, and means associated with each target carrying a prize, said means being adapted to be released by a properly directed projectile striking the associated target so as to deliver the prize to a patron.

2. A target game comprising a continuous target conveyor, a plurality of targets carried by said conveyor, a latch associated with each target adapted to support a prize in depending relation, a gun having a universal mounting at a fixed position with respect to the conveyor, said gun being adapted to discharge projectiles towards said targets, and means on each target adapted to be operated by a correctly directed projectile to operate the latch and release the prize associated with the target.

3. In a target game, a target conveyor, a target depending therefrom, an element carried by said target adapted to be struck by a projectile, a latch on said target adapted to support a prize, and means connecting said impact element and latch whereby the prize is released by a correctly directed projectile.

4. A target game comprising a continuous target conveyor, an electric motor adapted to operate said conveyor, a plurality of targets on said conveyor, means supporting a prize from said conveyor adjacent each target, and means on each target operable by impact for releasing the associated prize.

5. A target game comprising a cabinet, a continuous target conveyor, a compartment in the cabinet having a transparent wall, an opening in said compartment, a plurality of target carriages on said conveyor, a target on each carriage, a latch on each carriage adapted to support a prize, said targets and prizes being adapted to be exposed to view through said opening, means on each target operable by impact, means connecting said impact means to said latch, a gun mounted on said cabinet adapted to discharge projectiles towards said targets, and a duct extending downwardly from a location behind said opening adapted to discharge prizes released from said carriages.

6. A target game comprising a target conveyor, an electric motor adapted to operate said conveyor, targets carried by said conveyor, a gun adapted to discharge projectiles towards said targets under the control of a patron, and means adapted to render said gun inoperative when the motor circuit is open.

7. A target game comprising a target conveyor, an electric motor adapted to operate said conveyor, targets carried by said conveyor, a gun adapted to discharge projectiles towards said targets under the control of a patron, means adapted to render said gun inoperative, and a solenoid in series with the motor adapted to move said gun into gun operating relation.

8. A target game comprising a cabinet, a continuous target conveyor, an electric motor adapted to drive said conveyor, a compartment in the cabinet having transparent walls, an opening in

- 5 said compartment, a plurality of target carriages on said conveyor, a target on each carriage, a latch on each carriage adapted to support a prize, said targets and associated prizes being exposed through said opening for a limited time, means on each target operable by impact and adapted to release said latch, a gun mounted on the front wall of said cabinet adapted to discharge projectiles towards said targets, means tending to render said gun inoperative, a solenoid in the motor circuit adapted to actuate last said means to render the gun operative, and means adapted to deliver to a patron a prize released from a carriage.
- 10 9. A game comprising a moving support for a plurality of visible prizes, means for holding the prizes on the support, target devices cooperating with the holding means to release the several prizes as their corresponding targets are struck, means for propelling a projectile toward a target corresponding to a selected one of said prizes, and means for driving the moving support within the range of the propelling means.
- 15 10. A target game comprising a continuous target conveyor, a plurality of targets adapted to be exposed in succession for a limited time, a gun adapted to discharge projectiles toward said targets, means associated with each target carrying a prize, said means being adapted to be released by a properly directed projectile so as to deliver the prize to a patron, and coin controlled mechanism for moving said conveyor for a predetermined time.
11. A target game comprising a continuous target conveyor, a plurality of targets carried by said conveyor, a latch associated with each target adapted to support a prize, and means on each target adapted to be operated by a correctly directed projectile to operate the latch and release the prize associated with the target.
